PCM SUBSCRIBER CARRIER SYSTEM REMOTE TERMINAL WEATHERPROOF HOUSING OR SIMILAR ARTICLE

James R. Stewart, San Jose, and Donald G. Tweed,
Mountain View, Calif., assignors to GTE Automatic
Electric Laboratories Incorporated, Northlake, Ill.

Filed Nov. 1, 1972, Ser. No. 302,974

Term of patent 14 years

Int. Cl. D14—03

U.S. Cl. D26—14 A

FIG. 1

FIG. 2

FIG.3

FIG.4

FIG. 5

FIG. 6

FIG. 7

FIG. 1 is a front perspective view of a PCM subscriber-carrier system remote terminal weatherproof housing or similar article, showing our new design, and taken from the top and one side thereof;

FIG. 2 is a rear perspective view, taken from the top and one side thereof;

FIG. 3 is a front elevation view thereof;

FIG. 4 is a right side view thereof;

FIG. 5 is a top view thereof;

FIG. 6 is a rear elevation view thereof; and

FIG. 7 is a bottom view thereof.

We claim:

The ornamental design for a PCM subscriber-carrier system remote terminal weatherproof housing or similar article, as shown.
